Inventor.

Thomas W. Davies,
By George G. Wells,
Atty.

UNITED STATES PATENT OFFICE.

THOMAS W. DAVIES, OF ST. LOUIS, MISSOURI, ASSIGNOR TO HIMSELF AND
FRANK T. LONG.

DESIGN FOR A SHAFT-TUG.

SPECIFICATION forming part of Design No. 29,383, dated September 20, 1898.

Application filed June 17, 1898. Serial No. 683,756. Term of patent 3½ years.

To all whom it may concern:

Be it known that I, THOMAS W. DAVIES, a citizen of the United States, residing at St. Louis, in the State of Missouri, have invented 5 and produced a new and original Design for Shaft-Tugs, of which the following is a specification.

Figure 1 is an end elevation of the shaft-tug embodying my new design. Fig. 2 is an inner 10 side elevation as taken looking in the direction indicated by the arrow 2 in Fig. 1. Fig. 3 is the top plan view as seen looking in the direction of the arrow 3 in Fig. 1. Fig. 4 is vertical section taken on the line 4 4, Fig. 1, 15 and looking in the direction indicated by the arrow.

As shown in the drawings, the leading and essential feature of my new design for shaft-tugs consists of a substantially circular loop, 20 said loop being of considerable width longitudinally of its axes and said loop having two rectangular slots in its outer side and two rectangular slots in its inner side, said slots extending longitudinally of the axes of the 25 ring and substantially parallel to each other, and a box-shaped loop joined to the circular loop, the rectangular opening through the box-shaped loop being parallel with the rectangular slots in the circular loop, and there 30 being a slot extending from the upper outer rectangular slot of the circular loop through the bottom wall of the box-shaped loop to near the center of said wall, and there being a slot in the lower face of the upper wall of the box- 35 shaped loop in vertical alinement with said last-mentioned slot.

Referring in detail to the drawings, 5 is the substantially circular loop.

6 and 7 are the rectangular slots in the outer side of the loop. 40

8 and 9 are the rectangular slots in the inner side of the loop.

10 is the box-shaped loop.

11 is the slot extending from the upper outer slot 7 of the circular loop through the 45 bottom of the box-shaped loop, and 12 is the slot in the lower face of the upper wall of the box-shaped loop in vertical alinement with slot 11. Beads 13 and 14 extend around the circular loop 5 at its ends. The lower wall 50 15 of the box-shaped loop 10 is considerably longer than the upper wall 16, as shown in Fig. 3. An elevation 17 extends upwardly from the upper wall 16 of the box-shaped loop, and the slot 12 is formed in the lower face of 55 said elevation. The box-shaped loop is located between the beads 13 and 14, as shown in Figs. 2 and 3. At the junction of the box-shaped loop with the circular loop, immediately below the slot 11, is a rectangular opening 18, communicating with the bottom of said slot 11, as shown in Fig. 4, said opening 18 being formed through the material of the circular loop. The beads 13 and 14 serve to make the ends of the opening through the 60 65 circular loop slightly flaring or bell-mouthing.

I claim—

The design for a shaft-tug substantially as herein shown and described.

THOMAS W. DAVIES.
